CLAIM

The ornamental design for a tote bag, as shown and described.

DESCRIPTION

FIG. 1 is a front elevational view of a tote bag showing our new design;

FIG. 2 is a right side elevational view thereof;

FIG. 3 is a rear elevational view thereof;

FIG. 4 is a top plan view of the top flap and carrying strap; and

FIG. 5 is a bottom plan view of the tote bag.

The left side of the design is a mirror image of the right side of the design as shown in FIG. 2.
